PRIMING OR CHARGING ARRANGEMENT
FOR CENTRIFUGAL PUMPSJohn Southern, London, England, assignor to
Worthington Pump and Machinery Corpora-
tion, Harrison, N. J., a corporation of DelawareApplication July 22, 1938, Serial No. 220,641
In Great Britain February 18, 1938

1 Claim. (Cl. 103—113)

This invention relates to priming or charging arrangements for centrifugal pumps and is particularly concerned with motor-driven pump units for marine and other work where the unit 5 may be required to operate when submerged and under variable suction heads.

The invention will be described as applied to a vertical-shaft motor-driven self-priming pump unit of the general character described and illustrated in British Patent specification No. 470,208 but is not to be regarded as limited to pumps of this character.

An object of the invention is to provide a submersible pump unit having a skirting or bell-like enclosure for preventing water from entering the driving means of the pump and a priming pump for the centrifugal pump of the pumping unit, which priming pump is of the water-ring type and is arranged for unloading by discharge of its 20 sealing liquid and replacement of the discharged sealing liquid with air drawn from a supply within the bell-like enclosure.

With these and other objects in view, as may appear from the accompanying specification, the 25 invention consists of various features of construction and combination of parts, which will be first described in connection with the accompanying drawings, showing priming or charging arrangements for centrifugal pumps of the preferred 30 form the embodying invention, and the features forming the invention will be specifically pointed out in the claims.

In the drawings:

Figure 1 is a sectional elevation of a vertical-shaft centrifugal pump and combined priming pump arranged for motor drive and constructed in accordance with the invention.

Figure 2 is a sectional elevation of the priming pump taken on the line 2—2 of Figure 1.

Figure 3 is a sectional elevation of the float chamber, including the automatic valve for controlling the operation of the priming pump, taken on the line 3—3 of Figure 1.

The invention will be described by way of example as applied to a vertical-shaft motor-driven pump unit such as may be employed in marine work for bilge pumping and other duties under conditions which may involve the complete or partial submersion or flooding of the unit. Referring to Figure 1 of the drawings the casing of the single-stage centrifugal pump indicated generally at 1 forms the base of the unit and the electric driving motor (not shown) is mounted above the pump and suitably coupled to the vertical shaft 2. The motor is enclosed and the cas-

ing is extended downwards as shown at 3 to form an air bell which, as described in British Patent specification No. 446,771, will entrap air and prevent water from entering the motor casing when the unit is submerged. This casing 3 constitutes 5 a part of the framework which supports the driving motor.

Mounted directly upon the shaft 2 between the pump and the driving motor is the rotor 4 of the water-ring priming pump which is surrounded by 10 a casing supported upon the casing 1 of the centrifugal pump and sealed about the pump shaft. The priming pump is arranged so that its rotor may be unloaded automatically when the centrifugal pump is fully primed as described in 15 British Patent specification No. 470,208, but the construction of the pump is modified in certain respects as will now be described.

The casing of the priming pump includes an outer wall 5 and an inner wall 6, the latter forming the rotor chamber, and the two walls enclose an annular chamber 7 which forms a make-up reservoir for the pump. Water or any other suitable liquid may be used as the working medium for the pump. The chamber 7 is completely enclosed and is provided with a pair of upward extensions or limbs 8 and 9 which are curved inwardly as may be seen by reference to Figure 1 and thus serve also to support a bearing 10 for the pump shaft 2. These upward extensions are 25 not annular in plan as will be evident from a comparison of Figures 1 and 2 but form in effect a hollow arch and communicate at their upper ends through the passages 11 and 12. It will be appreciated that these hollow arched members 30 8 and 9 constitute in effect an air bell above the make-up reservoir.

The control of the priming pump when loading and unloading is effected by means of a valve member 13 housed in the casing of an enclosed 40 float chamber 14 which may conveniently be arranged outside the bell or skirting 3 of the motor enclosure. The float chamber is mounted upon a branch 15 of the main pump suction with which it communicates. A hollow float 17 is carried by a pivotally mounted arm 18 arranged to actuate, through a link 19, a pivoted lever arrangement indicated generally at 20 which is connected to the valve member 13. This lever arrangement is similar in all respects to that described in British Patent specification No. 470,208 and is adapted to actuate the valve member 13 with a snap action when the float 17 falls below a predetermined minimum level or rises above a predetermined maximum level. In this way the 45 50 55

valve member will always occupy either one or other of two end positions according to the water level in the float chamber. The valve member comprises a pair of spaced piston elements 21 and 22 which control the various unloading ports as hereafter described, and is also provided with a mushroom type of valve element 23 which is adapted to co-operate with a seating 24. This element, when closed, isolates the priming pump 10 from the float chamber.

Referring now to Figure 2 of the drawings, the suction or inlet side of the priming pump communicates with a chamber 25 and thence by means of a pipe 26 with a port 27 opening into 15 the upper part of the bore of valve 13. A non-return valve which may conveniently comprise a spring-pressed ball is preferably interposed in the pipe 26 to prevent liquid passing from the priming pump into the float chamber, although such 20 valve is not shown in the drawings. Immediately below the port 27 is a port 28 which communicates through a pipe 29 with the upper part of the make-up reservoir formed by the arched extensions 7 and 8. This connection will be seen 25 in Figure 2.

Towards the lower end of the bore of valve 13 is a port 30 communicating through a pipe 31 with a passage 32 and thence with the rotor chamber of the priming pump for the purpose 30 of unloading the latter. Immediately below the port 30 is a port 33 communicating by means of pipe 34 with the lower part of the make-up reservoir. A further port 35 is connected through a pipe 36 and passage 37 with the inner wall of the 35 rotor chamber and serves for the supply of make-up water to the rotor chamber.

The make-up reservoir 7 has an outlet 38 controlled by a non-return valve 39 which prevents any possibility of water entering the reservoir 40 from outside.

The discharge side of the priming pump communicates with a chamber 40 and thence through the vertical pipe 41 with the upper part of the reservoir chamber 7, the upper end of the said 45 pipe being located well above the level of liquid in the reservoir.

The operation of the combined centrifugal and priming pump unit will now be described. Assuming that air is present in the suction of the 50 centrifugal pump and the unit is started up, the valve 13 will be in the position shown in the drawings, the float 17 being in its lowest position and the float chamber filled with air. Under these 55 conditions the make-up reservoir will be in communication with the priming pump through the connecting pipe 34, ports 33 and 35, pipe 36 and passage 37, thus supplying the necessary liquid to form the water or sealing ring, the unloading port 30 being closed. The suction of the priming 60 pump is in communication through the pipe 26 with the float chamber by way of the open valve 23 and the pump will therefore commence to evacuate the suction of the centrifugal pump. The evacuated air is discharged by the priming 65 pump into the upper part of the reservoir 7 and any access escapes through the non-return outlet valve 39. It will be noted that the outlet 38 is within the skirting bell 3 and the air thus discharged will augment the supply of air within the 70 bell should the unit be submerged. As soon as evacuation is complete and the pump is primed the water will rise in the float chamber and actuate the valve 13 which by reason of the mechanism previously referred to will snap over 75 into its lower end position. All communication

between the priming pump and the float chamber is now cut off by the valve 23 and at the same time the suction side is placed in communication with the upper end of the make-up reservoir through the port 28 and pipe 29. The downward movement of the valve 13 also affords a connection between the ports 30 and 33 while cutting off the port 35 with the result that the sealing liquid of the pump is discharged by centrifugal force through the passage 32 and returns by way of 10 pipes 31 and 34 to the reservoir 7. It will be understood that in order to unload the pump in this way the sealing liquid discharged must be replaced by air or other gaseous medium. This is provided for by the opening of port 28 which 15 allows the air entrapped in the upper part or bell of the reservoir 7 to pass into the pump suction. The priming pump is now unloaded and its rotor is revolving freely in a chamber which contains air only and thus cannot add any appreciable load 20 to the main motor. This condition will continue until for any reason there is a loss of suction in the centrifugal pump sufficient to cause the water in the float chamber to fall and actuate the valve 13, upon which the priming pump will be automatically re-loaded.

The operations above will be carried out in the same way when the whole unit is submerged. The construction of the upper part of the make-up reservoir as an air bell into which the pump 30 discharges ensures that there will always be a supply of air to unload the pump and any excess will be discharged into the main air bell or skirting surrounding the motor and thereby affords an additional safeguard against the flooding of the 35 motor when the unit is submerged as this additional air will compensate for any loss by absorption or by other means. The provision of a non-return valve in this discharge prevents water from entering the make-up reservoir when, during sub- 40 mergence of the unit, the water level rises in the bell above such discharge outlet.

Thus the invention provides for a self-priming pump unit and for the automatic unloading of the priming pump under both submerged and un-submerged conditions independently of external air supply connections with their attendant disadvantages. It will be noted that when the centrifugal pump is operating at full capacity the priming pump is always unloaded and conversely 50 when the priming pump is loaded and operating the centrifugal pump will be operating under no-load or very low load conditions. It follows from this that the driving motor need only be rated for the full pump load and no allowance is necessary for the priming pump. This is an important consideration in large units as the power required by the priming pump may be quite considerable.

The feature of an enclosed sealing water reservoir for the priming pump prevents loss of water by evaporation both when standing and when running either submerged or unsubmerged.

The invention also provides an arrangement of the priming pump and its control gear which is 65 convenient and accessible. It is particularly to be noted that the automatic valve gear is located outside the main skirting of the motor thus greatly facilitating inspection and adjustment. The complete unit is simple in construction and has 70 few working parts, the weight is low and the efficiency is high.

It will be obvious that very many changes may be made in the form and arrangement of the various parts of the pump unit described above by 75

way of example, and the invention is in no way confined to this particular construction.

What is claimed is:

In a centrifugal pumping unit, a centrifugal pump, driving means therefor, a bell-like enclosure about said driving means for preventing entry of water into the driving means when the pump unit is submerged, a priming pump of the water-ring type connected to said centrifugal pump for priming it and unloaded by discharge of its sealing liquid, a container for air connected

to said priming pump whereby upon removal of the sealing liquid from the priming pump the liquid will be replaced by air, said priming pump having its discharge connected to said bell-like enclosure whereby discharge from the priming pump will assist in reducing the water level in the bell-like enclosure when the pump unit is submerged, and means preventing back-flow from the bell-like enclosure to the priming pump.
